D11-96. OR D16,711 EX

DESIGN.

—
J. T. MULLEN.
BADGE.

No. 16,711.

Patented May 25, 1886.

Witnesses.

John H. Murray
Fred C. Earle

James T. Mullen.
Inventor.

By Atty.

John B. Earle.

UNITED STATES PATENT OFFICE.

JAMES T. MULLEN, OF NEW HAVEN, CONNECTICUT.

DESIGN FOR A BADGE.

SPECIFICATION forming part of Design No. 16,711, dated May 25, 1886.

Application filed April 12, 1886. Serial No. 198,643. Term of patent 14 years.

To all whom it may concern:

Be it known that I, JAMES T. MULLEN, of New Haven, in the county of New Haven and State of Connecticut, have invented a new Design for a Badge; and I do hereby declare the following, when taken in connection with accompanying drawing and the letters of reference marked thereon, to be a full, clear, and exact description of the same, and which said drawing constitutes part of this specification, and represents a face view.

This invention relates to a design for a badge; and it consists in the configuration and ornamentation as shown in the accompanying illustration.

The body of the badge is in the form of a Maltese cross, A A A A representing the four arms, and each of the arms bordered by a plain margin, leaving a panel on the face. On the center of the cross is the representation of a shield, the position of the shield with relation to the cross being such that, the shield standing vertically, as shown in the illustration, the ends of the arms of the cross are each at an angle of forty-five degrees to the vertical position of the shield, and so that the spaces between the arms are respectively vertical and horizontal with relation to the shield. The sides of the shield are parallel with each other, the bottom extending downward in the center in a straight incline from each side. At the top the shield expands in a straight oblique line from each side, the top terminating in a straight horizontal line, with a right-angular upwardly-projecting point at the center. On 35 the face of the shield is the representation of a bound bundle of sticks with a tomahawk through it, resting upon an anchor and sword crossed. Above this ornamentation, on the face of the shield, are the letters "K of C;" 40 but such letters are not essential to the design, and may be omitted altogether or others substituted therefor, the essential feature of the design being the representation of the Maltese cross, with the representation of the shield of 45 the peculiar form shown in the illustration on the face of the cross, and with the ornament on the face of the shield, also shown in the illustration.

I claim—

The herein-described design for a badge, consisting in the representation of a Maltese cross with a shield on its face, the sides of which are parallel, with the bottom extending downward on an incline from each side toward the center, the upper end expanded to the right and left in an oblique line from each side, the top horizontal, with an angular upward projection in the center, and on the face of the shield the representation of a bound bundle of sticks with a tomahawk through it, resting upon the representation of an anchor and sword crossed, as shown in the accompanying illustration.

JAMES T. MULLEN.

Witnesses:

FRED C. EARLE,
J. H. SHUMWAY.